UNITED STATES PATENT OFFICE.

WILLIAM H. NODERER, OF CLEVELAND, OHIO.

DESIGN FOR A TOE-CLIP.

SPECIFICATION forming part of Design No. 24,369, dated June 4, 1895.

Application filed April 22, 1895. Serial No. 546,768. Term of patent 7 years.

To all whom it may concern:

Be it known that I, WILLIAM H. NODERER, a citizen of the United States, and a resident of Cleveland, county of Cuyahoga, State of Ohio, have invented and produced a new and original Design for Toe-Clips, of which the following is a specification, reference being had to the accompanying drawings, showing a part thereof.

- 10 Figure 1 is a side elevation of the form of toe-clip. Fig. 2 is a plan view of the same. Fig. 3 is a front elevation. These views are essential to completely illustrate all portions of the design.
- 15 The leading features of my design are, first, a main portion 1 bent at the forward extremity in an open curve at 2, and thence inclining upward and backward at 3 with an upwardly curved termination as shown. The
- 20 lower portion 4 is continued backward nearly as far and then turned downward at right an-

gles at 5. This portion is provided with the elongated opening 6. The entire part of the main portion is tapered gradually from the point from which the curve of the toe springs, ²⁵ and at the tapered extremity merges by the arcs 7 into the side extended guards 8 which have a rearward as well as a downward curve, and are provided with parallel sides from tip to base and terminate in semi-circles as shown ³⁰ clearly in Figs. 1 and 4. An upwardly curved tip 9 is placed centrally terminating the main outline as shown in Fig. 1, giving a slightly cruciform appearance to the plan view of the clip. ³⁵

What I claim is—

The design for a toe-clip as herein shown and described.

WILLIAM H. NODERER.
